UNITED STATES PATENT OFFICE.

EDWARD HARDIS, OF PASADENA, CALIFORNIA.

PUMP JACK.

Application filed December 15, 1924. Serial No. 756,075.

This invention relates to new and useful improvements in pump jacks designed primarily for use in connection with the pumps of oil wells, although not restricted to this particular field of use.

It is the principal object of the invention to provide a jack of novel construction which will produce a long steady stroke on the pump rod, will have no tendency to buckle or break said rod even when gas pockets are encountered, will operate with extreme ease and will be generally more efficient and desirable than the types of jacks now commonly used, provision being made 10 in the preferred form of construction, whereby the weight of the pump rod operating member, connected parts of the pump, and the load raised thereby are substantially counterbalanced, so that very little power 15 is needed to operate the jack and the pump.

A further object is to provide a pump jack construction which may be constructed substantially in its entirety, from well known stock steel and machine parts which 20 may be readily purchased on the market, so that the work and expense of manufacture will be cut down to the minimum.

Yet another object is to provide a structure in which effective provision is made for 25 lubrication.

With the foregoing and minor objects in view, the invention resides in the novel subject matter hereinafter described and claimed, the description being supplemented 30 by the accompanying drawings.

Figure 1 is a side elevation of a pump jack constructed in accordance with my invention.

Figure 2 is an enlarged vertical longitudinal sectional view, partly in elevation.

Figure 3 is a vertical transverse sectional view as indicated by line 3-3 of Fig. 2.

Figure 4 is a horizontal section on line 4-4 of Fig. 2.

Figure 5 is a side elevation of the reciprocating cross-head which is connected to the pump rod.

Figure 6 is an upper edge view of the cross head shown in Fig. 5.

The general frame structure of the jack is 50 in the form of a tower whose sills 1 are preferably formed of I-beams. Suitably secured to these beams are two channel-steel standards 2 which are disposed in opposed 55 relation and are suitably connected at their upper ends by a top frame 3. Secured to the

inner sides of the standards 2, between their inwardly extending flanges 4, are two short vertical pieces of channel steel 5 and 5^a, the flanges 6 of each metal channel 5-5^a being 60 extended inwardly toward the corresponding flanges of the other channel. In the construction shown, horizontally elongated metal plates 7 and similar plates 8 under them, are disposed in inwardly spaced relation with the body portions of the channels 5 and 5^a and are secured to the vertical edges of their flanges 6, in any preferred manner. The plates 7 are preferably somewhat longer than the plates 8 and they project beyond 70 the flanges 6, the projecting ends of one plate 7 being connected with the corresponding ends of the other plate 7, by horizontal plates 9 having a function to be hereinafter explained.

Appropriate bearings 10 are supported horizontally in openings formed through the body portions of the channels 5, through the adjacent portions of the standards 2, and through the plates 8, said bearings being 80 preferably of the roller type. In these bearings, short horizontal shafts 11 are rotatably mounted, said shafts having sprockets 12 on their inner ends, one sprocket being carried by each shaft. At the outer sides of these 85 sprockets, spur gears 13 are shown on the shafts 11, which gears mesh with driving pinions 14 on a horizontal shaft 15 which extends between the upper ends of the standards 2 and is rotatably mounted in 90 bearings 16 which are also preferably provided with anti-friction rollers. The shaft 15 is equipped with a sprocket 17 engaged by a vertical sprocket chain 18, this chain being driven by a sprocket 19 on a short 95 horizontal shaft 20 located near the lower end of the tower and rotatably mounted in appropriate bearings 21. The shaft 20 may be driven by any suitable means and I have illustrated a sprocket 22 and chain 23 for 100 this purpose.

Secured to the inner sides of the standards 2, near the lower end of the tower, I have shown steel channels 5^b and 5^c which correspond to the channels 5 and 5^a and 105 have their flanges 6^a connected by vertical plates 8^a and 8^b, the former being connected with the flanges of the channel 5^b and the latter being of greater height than the channel 5^c, so that the lower portion of the plate 8^a may support one of the bearings 21 for 110 the shaft 20, the other of said bearings be-

ing supported by the body portion of the channel 5^b and the adjacent portion of the contiguous standard 2. The upper portions of the plate 8^a and the channel 5^b, support one of a pair of bearings 10^a for two lower axially alined shafts 11^a, the other of said bearings 10^a being supported by the channel 5^c and the associated plate 8^b. The shafts 11^a are provided with sprockets 12^a, and two parallel vertically disposed sprocket chains 24 are trained around these sprockets and the driven sprockets 12, said chains being connected by a transverse horizontal roller 26 or some equivalent device, and wherever the term roller appears hereinafter, it is to be understood that this expression is intended to cover any member which might be used to connect the chains, in place of an actual roller.

20 The roller 26 is received in a horizontal guideway 27 of a suitably constructed cross-head 28 which is adapted for connection with a pump rod 29. To connect the cross-head with the pump rod, I preferably provide the former with vertically alined openings 30 in which the upper end of the rod may be secured by any preferred means. These openings are as near as possible to a vertical plane passing through the upwardly moving reaches of the sprocket chains 24, so that the upward pull on the crosshead 28, by means of the roller 26, will be exerted as near as possible to the rod, overcoming any liability of excessively canting the cross-head. To guide this cross-head, I provide a pair of vertical channel steel tracks 31 whose upper ends are suitably secured to the plates 9, said cross-head preferably having anti-friction rollers 32 which engage said tracks. The lower ends of the tracks 31 may well be secured to opposite side walls 33 of a lubricant containing receptacle 34 which is provided in the lower portion of the tower. This receptacle is positioned so that the shaft 20, sprocket 19, and chain 18, run in the lubricating oil contained in said receptacle, and if desired, an appropriate opening 35 may be provided in one of the side walls 33 to serve as a guide for filling the receptacle to the proper level.

55 A vertical tube 36 is secured in a fluid-tight manner to the bottom 37 of the receptacle 34, and said bottom is formed with an opening 38 at the lower end of said tube. This opening and tube receive the pump rod 29 and the tube extends to a point above the oil level of the receptacle 34 so that no wastage of oil may take place through said tube.

60 Mounted upon an appropriate bracket 39 at the upper end of the tower, I have shown a guide wheel 40 which may be in the form of a sheave or a sprocket, as occasion may demand. Trained around this wheel and

having its ends depending therefrom, is a flexible element such as a chain 41, one end of this chain being connected at 42 to the cross head 28, while its other end is provided with a weight 43 which may well be formed of sections carried by a rod 44, so that any desired number of such sections may be applied. The weight 43, acting on the chain or the like 41, substantially balances the weight of the cross-head 28, the pump rod 29, all other pump parts connected with said rod, and the weight of the quantity of oil lifted by the pump at each upward stroke. Thus, by providing this counterbalancing means, a pump jack is provided which permits operation of the pump with extreme ease, so that the expenditure of only a very small amount of power is necessary for its operation. Moreover, the effective lubrication provided for a number of the moving parts, by the oil receptacle 34, also plays an important part in producing a pump jack which will operate with as little friction as possible. Obviously, for lubricating parts which are not oiled from the contents of the receptacle 34, any desired provision may be made.

Unusually advantageous results have been obtained from a jack constructed in accordance with the present invention and on account of such advantages, the general construction herein disclosed, is preferably followed. However, within the scope of the invention as claimed, numerous modifications may be made.

I claim:—

1. A pump jack comprising a pair of opposed interconnected standards, upper and lower pairs of stub shafts between said standards, each pair being transversely alined and having their inner ends spaced apart, sprockets on said inner ends, a pair of chains trained over the sprockets, a cross head reciprocable between and carried by said chains and adapted for connection to a depending pump rod, a shaft arranged adjacent and in parallel relation to the upper stub shafts, gear connection between the last named shaft and the adjacent stub shafts, a sprocket at one end of said last named shaft, a stub shaft arranged below one of the lower pair of stub shafts, a sprocket on said stub shaft, a chain trained over the last named sprockets, and an oil receptacle partially enclosing the last named stub shaft and sprocket.

2. A pump jack comprising a pair of opposed standards each having laterally spaced vertical flanges, the flanges of one standard projecting inwardly toward those of the other standard, upper and lower plates spaced inwardly from said standards and disposed in vertical planes, said plates being secured to said flanges and the plates adjacent one standard being opposed to those of

the other standard, upper and lower horizontal shafts rotatably supported by said plates and the opposed portions of the standards, said shafts having upper and lower 5 pairs of axially alined spaced sprockets, a pair of sprocket chains trained around said sprockets, a roller connected at its ends to the two sprocket chains, a cross head between said chains having a horizontal guideway 10 receiving said roller, a pair of stationary vertical tracks for guiding said cross head, and means for driving at least one sprocket of each chain.

3. A pump jack comprising a pair of opposed standards each having laterally spaced vertical flanges, the flanges of one standard projecting inwardly toward those of the other standard, upper and lower plates spaced inwardly from said standards and 15 disposed in vertical planes, said plates being secured to said flanges and the plates adjacent one standard being opposed to those of the other standard, upper and lower horizontal shafts rotatably supported by said 20 plates and the opposed portions of the standards, said shafts having an upper pair of 25 axially alined spaced sprockets and a lower pair of axially alined spaced sprockets, a pair of sprocket chains trained around said sprockets, a roller connected at its ends to the two 30 sprocket chains, a cross head between said chains having a horizontal guideway receiving 35 said roller, a pair of vertical tracks for guiding the above named cross head, plates to which the upper ends of said tracks are secured, the last named plates being secured to the ends of certain of the aforesaid 40 vertical plates, means stationarily mounting the lower ends of said tracks, and means for driving at least one of the sprockets of each 45 of the sprocket chains.

opposed sides of said oil receptacle, means stationarily mounting the upper ends of said tracks, and means for driving at least one 50 of the sprockets of each of the sprocket chains.

4. A pump jack comprising a pair of opposed standards each having laterally spaced vertical flanges, the flanges of one standard 45 projecting inwardly toward those of the other standard, upper and lower plates spaced inwardly from said standards and disposed in vertical planes, said plates being secured to said flanges and the plates adjacent 50 one standard being opposed to those of the other standard, upper and lower horizontal shafts rotatably supported by said plates and the opposed portions of the standards, said shafts having an upper pair of 55 axially alined spaced sprockets and a lower pair of axially alined spaced sprockets, a pair of sprocket chains trained around said sprockets, a roller connected at its ends to the two 60 sprocket chains, a cross head between said chains having a horizontal guideway receiving 65 said roller, a pair of vertical tracks for guiding the above named cross head, plates to which the upper ends of said tracks are secured, the last named plates being secured to the ends of certain of the aforesaid vertical plates, means stationarily mounting the lower ends of said tracks, and means for driving 70 at least one of the sprockets of each of the sprocket chains.

In testimony whereof I have hereunto affixed my signature.

EDWARD HARDS.
